ADJUSTABLE TABLE FOR MASONRY SAWS

Robert Moffat and Leo J. Wright, Duquesne, Pa.,
assignors to Carnegie-Illinois Steel Corpora-
tion, a corporation of New Jersey

Application April 12, 1943, Serial No. 482,778

2 Claims.

(Cl. 125—13)

This invention relates to improvements in masonry saws of the character employed for cutting tiles, refractory shapes, etc., and more particularly to an adjustable table for masonry saws of the type illustrated in United States Letters Patent No. 2,171,024, granted August 29, 1939.

In employing such saws in industrial work, as for example, in the production of refractory shapes for furnace linings and the like, we have found the same impracticable for certain angular cuts. Such shapes as arch bricks, side skewes, feather edges and the like could not be readily produced on such saws, and necessitated hand chipping and grinding operations which materially increased the cost of the lining or other job being done.

Our invention has in view to provide an adjustable table mounted in proper relation to the cutting plane of the saw so as to enable the production of a selected angular cut face on the work-piece.

The invention further contemplates the construction and mounting of such a table to enable the same to be readily applied to existing masonry saws of the character stated.

Additional objects and advantages of our invention will become apparent from the following description taken in connection with the accompanying drawing, wherein:

Fig. 1 is a side elevational view of a masonry saw illustrating an embodiment of our invention therein;

Fig. 2 is an end elevational view thereof; and

Fig. 3 illustrates several refractory shapes which may be produced by the present invention.

Referring to the drawing, the masonry saw illustrated generally includes an open framework 2 including a pair of spaced parallel horizontal bed rails 3. At one end of the frame 2, a platform 4 is pivotally mounted on uprights 5, the latter being slotted at 6 for adjustment of the vertical position of said platform. Said platform rotatably mounts a masonry saw 7 and a motor 8 for driving the saw through a belt drive 9. The saw 7 is rotatable in a vertical plane and is adapted for swinging movement vertically in a plane centrally of the bed rails 3, said movement being controlled by the operator from a foot pedal 10 connected to the pivoted platform 4 by intervening linkage 11.

A work supporting carriage 12 is mounted on the bed rails 3 by means of grooved rollers 13, whereby the carriage 12 may be moved back and forth beneath the rotating saw 7. Our invention has to do with means for supporting the

work to be cut at an angle to the plane of the saw, to enable the cutting of tiles, refractory shapes, etc., like those illustrated in Fig. 3, wherein A is an arch brick, B is a side skew, and C is a feather edge, all of which shapes are so designated in the art and used in the construction of refractory linings for furnaces and the like.

All of such shapes may be cut from refractory blocks or bricks of rectangular form, and our invention enables the cutting of the desired forms therefrom on the job in accordance with the desired dimensions, including the production of one or more angular faces on said shapes.

For this purpose, the carriage 12 is provided with an adjustable table 14, hinged at 15 to one side of the carriage for pivotal movement of the table about an axis parallel to the plane of the saw 7, whereby the table may be angularly disposed in intersecting relation to the cutting plane 20 of the saw. The free end portion of the table 14 is provided with a centrally located segment 16, pivotally connected at 17 to the table and extending downwardly through an apertured clamping bracket 18 mounted on the carriage 12.

Bracket 18 is provided with a clamping screw 19 for engaging and holding the segment 16 in adjusted position. The segment 16 is in the form of an arcuate rod, curved about the pivotal axis of the table 14, said rod preferably bearing indexing marks thereon, graduated to indicate the angularity of the table 14 above the horizontal up to a maximum of 45 degrees, said indexing marks coacting with a selected fixed point upon the carriage 12, as for example, the upper face 35 of the bracket 18.

By means of said adjustable table 14, a masonry saw of the type illustrated may be readily adapted for cutting the shapes hereinbefore described. By adjusting said table to the proper angle in accordance with the relation of the angle of the face to be cut with one face of the refractory block or workpiece, the operator may readily cut a workpiece thereon by relative motion of the carriage 12 and saw 7. The operation 40 of our invention is clearly illustrated in the dotted line position of Fig. 2, wherein a refractory block is being cut to form a pair of side skewes B.

The adjusting segment 16, its attachment 17 to the table and the clamping bracket 18, are disposed so as not to interfere with the masonry saw structure proper, thereby readily permitting the installation of our invention to existing masonry saws without the necessity of materially altering the latter. Thus, the segment 16

moves in a path outwardly beyond the bed rails 3 and between the members of the open framework 2 without interference. A masonry saw provided with the adjustable table of our invention is thereby made capable of cutting in any special and angular shapes of tile, refractory bricks and the like.

Various changes and modifications are contemplated within the scope of the following claims.

We claim:

1. In a masonry saw of the character described having a work-receiving carriage and a saw movable in relation thereto, an adjustable work-receiving table on the carriage hinged thereto along one edge of said carriage for pivotal movement about an axis parallel to the cutting plane of the saw while intersecting said cutting plane,

a segment secured to the free end portion of the table, and means on the carriage for securing the segment and table in adjusted position.

2. In a masonry saw of the character described having a supporting framework, a work-receiving carriage and a saw movable in relation thereto, an adjustable work-receiving table on the carriage hinged thereto along one edge of said carriage for pivotal movement about an axis parallel to the cutting plane of the saw while intersecting said cutting plane, a segment secured to the free end portion of the table, and means on the carriage for securing the segment and table in adjusted position, said segment being disposed and movable in a path spaced in non-interfering position with said framework of the saw proper.

ROBERT MOFFAT.
